US0D1059486S

(12) **United States Design Patent** (10) **Patent No.:** **US D1,059,486 S**
(45) **Date of Patent:** **** Jan. 28, 2025**

(54) **BABY ACTIVITY LOGGING DEVICE**

(71) Applicant: **BabyLogger, LLC**, Roswell, GA (US)

(72) Inventor: **Lauren Longo**, Roswell, GA (US)

(73) Assignee: **Talli, Inc.**, Atlanta, GA (US)

(**) Term: **15 Years**

(21) Appl. No.: **29/703,164**

(22) Filed: **Aug. 25, 2019**

Related U.S. Application Data

(60) Division of application No. 15/787,350, filed on Oct. 18, 2017, now abandoned, which is a continuation-in-part of application No. 15/635,180, filed on Jun. 27, 2017, now abandoned.

(57)

CLAIM

The ornamental design for a baby activity logging device, as shown and described.

DESCRIPTION

FIG. 1 is a top perspective view of a baby activity logging device showing the new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines in the drawings depict portions of the baby activity logging device that form no part of the claim.
